REFRIGERATING APPARATUS

Estel C. Raney, Columbus, Ohio, assignor to
Ranco Incorporated, a corporation of Ohio

Application August 6, 1935, Serial No. 34,935

6 Claims. (Cl. 62—3)

The present invention relates to refrigerating apparatus and more particularly to refrigerating apparatus of the type employing a pressure reducing or "liquid-control" valve between the condenser and the evaporator.

One of the objects of the present invention is to provide a refrigerating apparatus employing an expansion valve wherein the valve is subjected to the pressure in the high pressure side 10 of the refrigerating system for opening the same and utilizing a thermo-responsive device which is associated with the valve in such a manner so as to provide decreasing and increasing closing pressure to the valve in response to decreasing and increasing temperature, respectively, of the refrigerant to be introduced into the low pressure side of the system.

Another object of the present invention is to provide an improved expansion valve for the refrigerating apparatus in which there is employed a thermostatic strip of metal subjected to the temperature of the refrigerant about to be introduced into the low pressure side of the apparatus and has the effect of decreasing and increasing its valve closing pressure in response to decreasing and increasing temperatures, respectively, of the refrigerant.

Further objects and advantages will be apparent from the following disclosure, reference being had to the accompanying drawing wherein a preferred form of embodiment of the present invention is clearly shown.

In the drawing:

Fig. 1 is a diagrammatic view of the refrigerating system employing the present invention.

Fig. 2 is a longitudinal sectional view of the pressure reducing or expansion valve.

Fig. 3 is a sectional view taken on line 3—3 of Fig. 2 and

Fig. 4 is a fragmentary view in elevation of the right hand end of a tube which receives the valve stem.

Referring in general to the drawing, there is provided, an evaporator 28 which receives liquid refrigerant from a pipe 21. This liquid refrigerant enters at the bottom of the evaporator and when it is vaporized, it is withdrawn from the upper part of the evaporator through a pipe 22. The pipe 22 is connected to the low pressure side 45 of a compressor 23 wherein it is compressed and delivered into a condenser 26. This condenser 26 may be cooled in any suitable manner as by a stream of air or by water if desired. The refrigerant from the condenser 26 flows by pipe 27

to the expansion valve 28 whence it is delivered by the pipe 21 to the evaporator 20. The evaporator may be of the intermittent type if desired in which case the compressor will be started and stopped in the usual manner by a switch which is either responsive to the pressure or temperature in the evaporator or which is responsive to the temperature of the environment cooled by the evaporator.

The expansion valve 28 includes a valve body 30 and is herein shown constructed of three major parts which are the cup 31, the cover 32 therefor and the tube or sleeve 33 leading from the cup 31. These three parts form a chamber 34 on the high pressure side of the refrigerating system, the refrigerant being introduced into the chamber 34 through the cover 32. At the outlet of the chamber 34 there is provided a hardened inserted valve seat 36. A valve 37 is arranged to rest upon the seat for controlling the flow of refrigerant from the chamber 34 to the pipe 21. A spring 38 normally urges the valve 37 towards the seat. This spring 38 is interposed between the valve and a coupling 39 screw threaded into the tube 33. A stem 40 on the valve 37 extends through the tube 33 and into the cup 31. Seats or shoulders are formed on the stem 40 within the cup 31 and is herein shown as comprising a pin 41. The tube 33 extends within the cup and is provided at the end thereof with V shaped 35 seats or shoulders 42 on opposite sides of the stem 40. A generally U-shaped or hair pin shaped thermostatic strip 43 preferably formed of bi-metallic material is provided with seat engaging portions for engaging the seats on the valve stem and the seats on the tube 33. For this purpose the strip 43 is provided with depressed portions 44 which cooperate with the pin 41 and is provided with depressed portions 45 40 which cooperate with the V-shaped seats 42 on the tube 33. The bi-metallic strip 43 is formed of resilient material so that when it is depressed and placed so that the seats thereon are in cooperative relation with seats 41 and 42 on the valve stem and the tube 33, it will be maintained 45 in this position due to its resiliency.

It will be noted that pressure on the high pressure side of the refrigerating system is exerted directly upon the valve 37 and tends to open the valve in opposition to spring 38. The bi-metallic strip 43 is arranged so that with increasing temperature within the chamber 34 it will increase its closing pressure on the valve 37 and conversely, as the temperature within the chamber 34 de-

creases, its valve closing pressure will be decreased. Therefore, it is apparent that when warm gaseous refrigerant flows into the chamber 34 from the condenser the strip 43 will increase its valve closing pressure. Due to the thickness and the size of the strip, the pressure exerted thereby is limited to such an extent that in the event that there is an excessive pressure considerably above normal, within the system, the pressure exerted by the strip and the spring is insufficient to counteract the opening pressure of the refrigerant on the valve 37 whereby the valve 37 will release the pressure within the high pressure side of the system prior to attainment of the bursting pressure on the high pressure side. It is to be understood that this opening at this time occurs under only abnormal conditions. Normally, when gas is present at the valve 37, the strip 43 will tend to hold the valve closed and when the liquid cools, the strip 43 will also cool so as to decrease the valve closing pressure thereof and, when the temperature of the liquid decreases to a predetermined point, the pressure within the high pressure side of the system will open the valve 37 and thereby admit liquid refrigerant into the low pressure side of the system. It is to be understood that the temperature of the liquid within the chamber 34 is cooled to a lower temperature than the temperature of the refrigerant when it condenses in the condenser. In other words, there is a cooling effect of the refrigerant by the lower part of the condenser and the environment surrounding the pipe and the chamber 34 so that during normal operations the liquid in the chamber 34 is colder than the refrigerant at the time it condenses.

From the foregoing it will be seen that there is provided a refrigerating system in which, during normal operation, no refrigerant will flow from the high pressure side of the system into the low pressure side unless liquid refrigerant is present but as soon as cooled liquid refrigerant is present at the valve, it is delivered to the low pressure side. Also it is apparent that there is provided a refrigerating system which will always fail safely, that is, in case the strip 43 should break, the pressure within the high pressure side of the system will be exerted on the valve for opening the same. Also in the event that the condenser is not functioning properly, the valve 37 will open before a bursting pressure is created on the high pressure side.

Preferably the entire valve structure is permanently sealed and to accomplish this, the cover 32 is flared outwardly and then bent inwardly over a flange 46 on the cup 31. The inwardly bent portion of the cover 32 is shown at 41. If desired a screen 48 can be interposed between the cover 32 and flange 46 of the cup 31 for preventing dirt or scale or any injurious matter from coming in contact with the valve 37. The joint between the flanges 46 and 47 is sealed as by solder. Also the tube 33 is provided with a flange 49 which rests against the cup 31 at which point these elements are sealed together as by solder. The coupling 39 is screw threaded into the tube 33 to such an extent as to give the proper tension of the spring 38 and then the tube 33 is crimped as at 50 to bind the coupling in position and the joint between the coupling 39 and tube 33 is also soldered. The end of the tube 26 which connects with the cover 32 is also soldered into position and likewise the pipe 21 is soldered in coupling 39.

While the form of embodiment of the present invention as herein disclosed constitutes a pre-

ferred form, it is to be understood that other forms might be adopted, all coming within the scope of the claims which follow.

I claim:

1. In a refrigerating system, a combination expansion and safety valve for controlling the flow of refrigerant from the high pressure side of the system to the low pressure side thereof, comprising in combination, a valve body having a high pressure chamber adapted to be connected with the high pressure side of the refrigerating system and having a stationary valve seat at the outlet thereof, a valve cooperating with the seat and adapted to open in response to pressure within the chamber, and a resilient thermo-responsive strip disposed within the chamber and biased to be frictionally engaged between a wall of the chamber and a portion of said valve and constructed to act with decreasing or increasing valve closing force on the valve in response to decreasing or increasing temperatures, respectively, of the refrigerant in said chamber.

2. In a refrigerating system, a combination expansion and safety valve for controlling the flow of refrigerant from the high pressure side of the system to the low pressure side thereof, comprising in combination, a valve body having a high pressure chamber adapted to be connected with the high pressure side of the refrigerating system and having a stationary valve seat at the outlet thereof, a valve cooperating with the seat and adapted to open in response to pressure within the chamber, and a resilient hair-pin-shaped thermo-responsive strip disposed within the chamber and biased to be frictionally engaged between a wall of the chamber and a portion of said valve and constructed to act with decreasing or increasing valve closing force on the valve in response to decreasing or increasing temperatures, respectively, of the refrigerant in said chamber.

3. In a refrigerating system, a combination expansion and safety valve for controlling the flow of refrigerant from the high pressure side of the system to the low pressure side thereof, comprising in combination, a valve body having a high pressure chamber adapted to be connected with the high pressure side of the refrigerating system and having a stationary valve seat at the outlet thereof, a valve cooperating with the seat and adapted to open in response to pressure within the chamber, and a thermo-responsive strip disposed within the chamber and connected with the valve and constructed to act with decreasing or increasing valve closing force on the valve in response to decreasing or increasing temperatures, respectively, of the refrigerant in said chamber, said body and valve each forming a seat for the strip and said strip having a depressed portion at each end thereof and forming seats cooperating with the seats of the body and valve, said strip being formed of resilient material and biased to frictionally cause retention of the seats in cooperative relation.

4. In a refrigerating system, a combination expansion and safety valve for controlling the flow of refrigerant from the high pressure side of the system to the low pressure side of the system, comprising in combination, a valve body having a high chamber adapted to be connected with the high pressure side of the refrigerating system and having a valve seat at the outlet thereof, a valve cooperating with the seat, said valve being responsive to the pressure within the chamber and tending to open in response to pressure within the

- chamber, thermal-responsive means adapted to respond to the temperature of the refrigerant in the high pressure side of the system, said means being connected with the valve and tending to hold the valve closed with increasing force upon increase of temperature of the refrigerant, the construction and arrangement of the thermal-responsive means being such that the effective valve closing force thereof increases slower than the effective valve opening force by pressure upon increase in temperature and pressure of the refrigerant within the chamber when the refrigerant is in the gaseous state. 5
5. In a refrigerating system, a combination expansion and safety valve for controlling the flow of refrigerant from the high pressure side of the system to the low pressure side of the system, comprising in combination, a valve body having a high chamber adapted to be connected with the high pressure side of the refrigerating system and having a valve seat at the outlet thereof, a valve cooperating with the seat, said valve being responsive to the pressure within the chamber and tending to open in response to pressure within 10 the chamber, thermal-responsive means within the chamber and responsive to the temperature of the refrigerant in the chamber, said means being connected with the valve and tending to hold the valve closed with increasing force upon increase of temperature of the refrigerant, the construction and arrangement of the thermal-responsive means being such that the effective valve closing force thereof increases slower than the effective valve opening force by pressure upon increase in temperature and pressure of the refrigerant within the chamber when the refrigerant is in the gaseous state. 15
10. The effective valve opening force by pressure upon increase in temperature and pressure of the refrigerant when the refrigerant is in the gaseous state. 20
20. In a refrigerating system, a combination expansion and safety valve for controlling the flow of refrigerant from the high pressure side of the system to the low pressure side of the system, comprising in combination, a valve body having a high chamber adapted to be connected with the high pressure side of the refrigerating system and having a valve seat at the outlet thereof, a valve cooperating with the seat, said valve being responsive to the pressure within the chamber and tending to open in response to pressure within 25 the chamber, a bi-metal thermostat within the chamber and responsive to the temperature of the refrigerant in the chamber, said thermostat being connected with the valve and tending to hold the valve closed with increasing force upon increase of temperature of the refrigerant, the construction and arrangement of the thermostat being such that the effective valve closing force thereof increases slower than the effective valve opening force by pressure upon increase in temperature and pressure of the refrigerant within the chamber when the refrigerant is in the gaseous state. 30
